UNITED STATES PATENT OFFICE

HEINRICH ROMBERG AND HERMANN SCHULER, OF DUSSELDORF, GERMANY, ASSIGNEES
TO RHEINISCHE METALLWAAREN- UND MASCHINENFABRIK, OF DUSSELDORF-
DERENDORF, GERMANY, A CORPORATION OF GERMANY

FIREARM

Application filed January 5, 1932, Serial No. 584,855, and in Germany January 9, 1931.

It has already been proposed to alter the starting velocity of projectiles of fire arms by partly conducting the driving gases, developed behind the projectile, out of the path of the projectile and thereby to obtain, instead of the sweeping or scouring trajectory of the projectile, a curved trajectory having a steeper angle of incidence which allows an effective sweeping or scouring of nearer objects behind shelters or covers. For this purpose the part of the barrel having furrows or grooves is provided with lateral holes which may be more or less throttled by means of a control member to conduct away a smaller or greater portion of the driving gases, so that this portion of the gases is prevented from acting upon the projectile. By drawing off gases in such a manner at the middle or front part of the barrel, a very small reduction of the starting velocity of the projectile may be obtained only, as the driving gases in the shape of a closed jet pass with great velocity over the drawing off holes without the desired amount of gas being conducted away laterally. Moreover the front edges of the holes, provided in the barrel and acting like a knife, scrape chips off the projectile passing along, and such chips accumulate in the holes which therefore soon become clogged.

To be able to use in a weapon cartridges having an excessive charge, the part of the cartridge chamber surrounding the projectile behind the furrows or grooves has already been provided with holes, and by means of the annular space or radial clearance provided in this manner between the projectile and the wall of the chamber, a portion of the driving gases has been drawn off by way of the front portion of the barrel without being used. These gases, passing along the projectile in the form of a blow pipe flame, cause, however, a strong burning out of the barrel, and moreover, the projectile is not guided at the beginning of its movement.

According to the invention the driving gases are drawn off by means of an annular space or radial clearance in the cartridge chamber which space surrounds the projec-

tile behind the rear end of the furrows or grooves and to which the channels leading outwards or an additional space are connected. The projectile, extending now already before the firing partially over the drawing off portion in the barrel, slides, at the beginning of its movement completely over the holes, without forming chips and a sufficient amount of the driving gases escapes, as these gases are developed only after the drawing off holes have been uncovered and therefore have still a very small forward velocity. The gases passing through the annular space may be conducted into a closed additional space which, acting as an enlargement of the combustion space, reduces the maximum gas pressure and therefore the medium gas pressure also. The driving gases may also directly be conducted into the atmosphere by way of an intermediate chamber and in this way they are absolutely prevented from acting upon the projectile. Particularly suitable for the drawing off of the driving gases is an annular space or radial clearance in the barrel in front of the cartridge shell the width of which may be adjusted for allowing a smaller or greater amount of gas to pass through in the time unit and which also may be completely closed.

In the accompanying drawing the invention is shown by way of example in connection with the barrel of an automatic machine gun a portion of which is illustrated in longitudinal section.

The barrel is composed of two parts, a hind or rear part *a*, containing the cartridge chamber and afterwards called "cartridge chamber", and a front portion *b* in which the furrows or grooves *b*₁ are cut. The part *b* is screwed into a female thread *a*₁ of the cartridge chamber *a* and may be, by means of a locking device *d*₁, *d*₂, adjusted and fixed therefrom in a position in which the front face *b*₂ of the outer conical hind end *b*₃ of the barrel part *b* is in contact with a corresponding counter face *a*₂ of the cartridge chamber to positions in which a space of different width is formed between these two surfaces. The mouth piece *a*₃ of the car-

tridge chamber is hollow, so that a free annular space *e* remains surrounding the hind or rear end *b*₃ of the portion *b* provided with the furrows or grooves *b*₁. This space *e* forms the continuation of the space *c*. A plurality of bores *a*₄, provided around the mouth piece *a*₃ and extending in the direction of the barrel or in a somewhat outwardly inclined direction, lead from the space *e* into the atmosphere or into a jacket surrounding the barrel.

If projectiles are to be fired with the normal starting velocity in a sweeping or scouring trajectory, the portion of the barrel provided with the furrows or grooves *b*₁ is screwed into the cartridge chamber *a* until its hind or rear face *b*₂ contacts with the counter face *a*₂ of the cartridge chamber *a* in which position the part *b* is locked against rotation by means of the locking device *d*₁, *d*₂. Then all the gases developed by the driving charge of the cartridge will be active to propel the projectile. To obtain a more curved trajectory having a steeper angle of incidence, the portion *b* of the barrel, having the furrows or grooves *b*₁, is, by screwing out, shifted to the front in the cartridge chamber *a*, so that between the surface *b*₂, *a*₂ of these two parts an annular space *e* or radial clearance of determined width is formed through which, according to the width adjusted, a smaller or greater portion of the driving gases developed behind the projectile is, partially used only or not used at all, passed into the space *e* and from there, by way of the holes *a*₄, into the atmosphere. The effect of the different positions of the barrel portion *b* in the cartridge chamber *a* and of the space *e* which is formed by these two parts upon the starting velocity of the projectile may be indicated on the outside by means of a suitable indicating device, so that the proper adjustment may be obtained. A width of the slot of about 0.8 mm. is sufficient to reduce the normal starting velocity of an infantry projectile to about half the velocity.

The adjustability of the cross section of the drawing off channels and also of the width of the slot *c* is not absolutely necessary. In the case of weapons having an exchangeable barrel, besides the normal one-part barrels, barrels provided with a fixedly adjusted space of a determined width between the portion having the furrows or grooves and the cartridge chamber may be carried with which serve the purpose of firing standard projectiles under a perfectly determined trajectory altered with regard to the normal trajectory.

We claim:

1. In a fire arm having a device for altering the starting velocity of the projectile by conducting a portion of the driving gases out of the barrel, a cartridge chamber, a female thread at the front end of said chamber, a barrel portion having furrows or grooves, a

thread at the hind or rear end of said barrel portion fitting said female thread, said barrel portion having a conical rear end extending into a correspondingly shaped portion of said cartridge chamber in such a manner, that an annular space is formed between said parts which communicates with bores provided in said cartridge chamber opening into the atmosphere.

2. In a fire arm having a device for altering the starting velocity of the projectile by conducting a portion of the driving gases out of the barrel, a cartridge chamber, a female thread at the front end of said chamber, a barrel portion having furrows or grooves, a thread at the hind or rear end of said barrel portion fitting said female thread, said barrel portion having a conical rear end extending into a correspondingly shaped portion of said cartridge chamber in such a manner, that an annular space is formed between said parts which communicates with an additional space formed between the inclined surfaces of both said parts and which in turn communicates with said bores provided in said cartridge chamber.

3. In a fire arm is claimed in claim 1 in which the width of said annular space is adjustable by more or less screwing home said barrel portion fitting said cartridge chamber.

4. In a fire arm having a device for altering the starting velocity of the projectile by conducting a portion of the driving gases out of the barrel, a cartridge chamber, a female thread at the front end of said chamber, a barrel portion having furrows or grooves, a thread at the hind or rear end of said barrel portion fitting said female thread, said barrel portion having a conical rear end extending into a correspondingly shaped portion of said cartridge chamber, a locking member carried by said cartridge chamber and a plurality of locking members provided at said barrel portion and cooperating with said first mentioned locking member to fix the two parts screwed together in the adjusted position against relative rotation.

In testimony whereof we affix our signatures.

HEINRICH ROMBERG. 115
HERMANN SCHULER.
